UNITED STATES PATENT OFFICE.

GEORGE FREDERICK RUSH, OF CHICAGO, ILLINOIS.

LAMP-SOCKET

1,106,974.

Specification of Letters Patent. Patented Aug. 11, 1914.

Application filed June 13, 1913. Serial No. 773,442.

To all whom it may concern:

Be it known that I, GEORGE FREDERICK RUSH, a citizen of the United States, residing at Chicago, in the county of Cook and State of Illinois, have invented a certain new and useful Improvement in Lamp-Sockets, of which the following is a specification.

This invention relates to electric lamp sockets and its object is to provide such a device of unusually neat appearance and compact form, which can be easily and cheaply constructed of very few parts.

The invention consists in a device capable of carrying out the foregoing objects, and more particularly one in which the usual cylindrical metallic lamp receiving shell is secured to an insulating base by very simple frictional means without the aid of other fastening parts.

The invention also consists in details of construction which will be more fully set forth hereafter.

In the drawings, Figure 1 is a vertical sectional view through a mechanism which illustrates this invention in its preferred form. Fig. 2 is a top plan view of the parts illustrated in Fig. 1. Fig. 3 is an inverted plan view of the same parts. Fig. 4 is a plan view of the metallic shell member removed from the base. Fig. 5 is a bottom plan view of the central terminal for a lamp to be inserted in the socket, the same taken out from the central portion of the parts illustrated in Fig. 3. Fig. 6 illustrates a modified form of the tubular member.

In constructing the preferred form of this device, a cylindrical base member 10 of insulating material is provided, preferably closed at one end by a bottom 12 integral therewith, the opposite end being provided, if desired, with a flange 14 for any desired purpose. The base, therefore, closely resembles a cup having sides 10 and a bottom 12.

Extending inside of the base member 10 from the bottom 12 thereof is a central projection or lug 16 through which is an opening or recess 18 for the usual central terminal of the socket terminating in a central contact located in recess 20 within the main socket. This central terminal and its details are well known in the art and of itself forms no part of this invention. The outer wall of the central projecting lug 16, is preferably provided with a series of circum-

ferential notches 22 or fluting, and the interior cylindrical wall 24 of the base member 10 is preferably left in a more or less roughened condition when made. Inside of this base member 10 is inserted the usual cylindrical metallic terminal shell 26 provided on its circumference with screw threads, as shown, for engagement by the threads on the outside of the electric lamp stem which is to be inserted therein in the ordinary manner. This is in other words, in these particulars, the standard shell of commerce. This standard metallic shell 26 is secured in position in the base 10 preferably by providing upon its lower outer circumference a plurality of outwardly turned teeth 30 engaging the interior wall 24 of the base and preferably also, by providing a plurality of inwardly turned teeth 32 extending toward and engaging the central lug 16 in the notches 22, heretofore described. The tubular member or shell 26 is preferably made of spring metal so that the inwardly turned teeth 32 and the outwardly turned teeth 30 are in fact springs which through this fact forcibly engage the respective parts of the insulating base. The forms of these spring members may be varied without departing from the invention. They may even be made as one continuous flange around and a part of the shell 26, see flange 30a, Fig. 6.

In the construction of the device, the base and the central shell member 26 are, of course, made separately. Then the shell is inserted inside the base to the position shown in Fig. 1 in which position the sets of teeth 30 and 32 frictionally engage the base and thus retain and secure the shell 26 in position as shown, without the aid of other securing devices.

Electricity is conducted to the internal cylindrical shell 26 through a wire, not shown, which passes through a hole 34 provided for the purpose in the base, said wire being soldered to the shell 26 before the parts are assembled, and shoved through said hole 34 simultaneously with the insertion of the shell 26, as heretofore described.

Having thus described my invention, what I claim as new and desire to secure by Letters Patent is:

1. A lamp socket device including a hollow base member having a recess therein, a tubular shell of less diameter than the recess in the base inserted in said recess said

shell having on one portion outwardly pointed teeth whose outer ends lie in a curve of normally greater diameter than the interior of the base so that when the shell 5 is inserted in the base, the teeth frictionally press against the wall of the base to hold the shell therein.

2. A lamp socket device including a hollow base member of insulating material having a recess therein, a tubular metallic shell of less diameter than the recess in the base, and of suitable length to be inserted wholly inside the base, having on one end outwardly pointed teeth whose outer ends lie in 15 a curve of normally greater diameter than the interior of the base so that when the shell is inserted in the base, the teeth frictionally press against the wall of the base to hold the shell therein.
- 20 3. In a device of the class described, a cup shaped base member of insulating material having a cylindrical opening therein, a central lug projecting from the interior of the base of the cup, and a cylindrical metallic

shell inserted in said opening in the base, 25 said shell being of a diameter intermediate between the base and lug and formed with inwardly turned teeth at one end adjacent to the lug and outwardly turned teeth at the opposite end extending toward the base, 30 the diameter of the opening inclosed by the points of the inwardly turned teeth being normally less than the diameter of the lug and the diameter of the curve on which points of the outwardly turned teeth lie, being normally greater than the diameter of the opening in the base, whereby the respective sets of teeth frictionally engage the lug and the base respectively and thus hold the shell in place upon the base.

In witness whereof, I have hereunto subscribed my name in the presence of two witnesses.

GEORGE FREDERICK RUSH.
